(57) **CLAIM**

We claim the ornamental design for an elongated aquarium, as shown and described.

DESCRIPTION

FIG. 1 is a perspective view of the elongated aquarium.

FIG. 2 is a front view of the elongated aquarium.

FIG. 3 is a rear view of the elongated aquarium.

FIG. 4 is a right side view of the elongated aquarium.

FIG. 5 is a left side view of the elongated aquarium.

FIG. 6 is a top view of the elongated aquarium; and,

FIG. 7 is a bottom view of the elongated aquarium.

The broken lines in the drawings define boundary lines and form no part of the claimed design.
